Atty.

UNITED STATES PATENT OFFICE

PAUL HERTZSCH, OF MARKRANSTADT, NEAR LEIPZIG, GERMANY

APPARATUS FOR DRYING AND CLEANING HIDES

Application filed December 21, 1932, Serial No. 648,179, and in Germany August 2, 1932.

My invention relates to apparatus for drying and cleaning hides, and more particularly to an apparatus in which the hides are dried and cleaned through the medium of a gas current, preferably hot air, and a cleaning agent having solid particles such as sawdust, sand or the like, which is entrained by the gas. The hides are subjected to the action of the gas and solids in a rotary member or drum, as described in my copending application for patent of the United States, Serial No. 382,729, filed August 1, 1929.

In the apparatus described in my said copending application mechanical means, such as perforated plates, are provided for mechanically separating the solid particles from the gas leaving the rotary member. Such mechanical separation involves certain drawbacks. Firstly the openings in the perforated plates must be smaller than the particles of the cleaning agent and it is obvious that frequent clogging of such narrow openings is inevitable. Such clogging however involves the shutting down of the apparatus, allowing it to cool, opening the rotary member, cleaning the perforated plates and re-heating the apparatus. Apart therefrom the velocity of the gas current, i. e. the quantity of gas flowing through the apparatus per unit of time, is limited by the small area of the openings in the perforated plates, and further the mechanical means retain the solid particles or cleaning agents in the rotary member where the vapor which is liberated from the wet hides, gradually imbibes them with moisture and reduces their efficiency.

It is an object of my invention to improve an apparatus of the kind described with a view to eliminating these drawbacks. To this end, instead of the mechanical means provided in the apparatus referred to for retaining the particles, I provide pneumatic means for separating the particles and for returning them to the rotary member. The particles are separated from the gas which has left the rotary member and in which, in addition to the particles, the vapor liberated from the wet hides is suspended. The mechanically purified mixture of gas and vapor is discharged from the apparatus while the

separated solid particles are delivered to the gas which flows toward the rotary member, i. e. returned to the member. In this manner, the cleaning agent is continuously circulated through the apparatus while the gas is discharged at one end, and fresh gas drawn in at the other end. Preferably, the separated particles are dried before being delivered to the gas flowing toward the rotary member. Drying may be effected by heating the pneumatic separator.

By dispensing with the perforated plates provided in the apparatus described in my said copending application, the quantity of gas flowing through the apparatus per unit of time is much increased and the drying and cleaning operation is accelerated in proportion. Clogging by the cleaning agent is an obvious impossibility. By heating the separator, the particles of the cleaning agent are dried and heated before they are returned to the rotary member and this increases their efficiency. It is not necessary that the particles should be dried by heating the separator, but separate means for drying and/or heating the particles may be provided if desired.

In my novel apparatus there is a continuous circulation of the cleaning agent through the rotary member. The particles of the agent are dried while at the same time fresh gas is continuously admitted to the apparatus and the gas in which vapor is suspended, is discharged. Notwithstanding the greater quantities of gas flowing through the apparatus at higher velocity, and the discharge of the mechanically purified mixture of gas, and vapor, sufficient quantities of cleaning agent will always be present in the rotary member.

In the drawing affixed to this specification and forming part thereof an apparatus embodying my invention is illustrated diagrammatically and partly in section by way of example.

Referring now to the drawing, *a* is the rotary member or drum which, as described in my said copending application, is equipped with slabs *p* on the inner face of its barrel, and *e* and *f* are hollow trunnions or journals

which are connected to the end walls of the drum *a* and mounted in bearings of the uprights *h* and *i*. *t* is a stuffing box on the trunnion *e* and *t'* is a stuffing box on the 5 trunnion *f*. *b* is a pulley on the trunnion *e* for rotating the drum *a*. *k* is a fan to which rotation is imparted by any suitable means (not shown), and whose suction pipe is connected to the trunnion *f* by the stuffing box 10 *t'*. *c* is the suction pipe of the fan *k* which is connected to the trunnion *e* through the stuffing box *t*. *q* is a heater of any suitable kind, for instance, a steam jacket, which is arranged above the drum *a* and surrounds 15 the upper horizontal reach of the suction pipe *c*, through whose open end air is drawn into the fan *k*. Obviously, instead of air, any other gas might be drawn into the apparatus from a suitable reservoir (not 20 shown).

The heater *q* is arranged in the immediate vicinity of the drum *a* so that it radiates a portion of its heat to the drum. Preferably, the drum and the heater are surrounded by a 25 suitable casing or cowl (not shown) for holding the air which is heated by the heater *q*, in contact with the walls of the drum.

Instead of the perforated plates at the openings of the trunnions *e* and *f* in the end 30 walls of the drum *a*, as described in my said copending application, the openings are here protected by wide-meshed gratings *u* which only retain the hides but do not interfere with the free flow of the air and the particles 35 of cleaning agent suspended therein, from one end of the drum to the other.

m is a pneumatic separator here shown as a vertical cylinder with tapered upper and lower ends. At its upper end the separator 40 *m* is connected to the delivery side of the fan *k* by a pipe *l* and equipped with a vertical discharge pipe *v*. The tapered lower end of the cylinder *m* is equipped with a comparatively narrow outlet *o* for the separated particles.

r is a heating jacket which surrounds the separator *m* and its tapered ends and may be heated by any suitable means. In the example illustrated, the jacket is connected to 50 the heater *q* at its lower tapered portion by a pipe *x*. *s* is a discharge pipe for the heating medium at the upper tapered portion of the jacket *r*. Heating medium such as steam, hot air, hot water or the like, is admitted to 55 the heater *q* through a pipe *w*, conducted to the jacket *r* of the separator *m* through the pipe *x* and discharged from the jacket through the pipe *s*. It is understood that the heating system for the separator and the 60 drum may be modified in various ways.

g is a pipe which extends upwardly from the vertical portion of the suction pipe *c* and, with its upper flaring end, surrounds at some clearance the lower tapered portions of 65 the separator *m* and the jacket *r*, and the

outlet *o* of the separator; *n* is a flange at the upper end of the flaring portion of the tube *d*, *y* is a hole or slot in the flange at the side of the tapered lower portion of the heating jacket *r*, and *z* is a valve which is mounted 70 to turn on the flange *n* and has an opening which is adapted to register with the opening of slot *y*. Obviously, any number of openings may be provided in the flange *n* and in the rotary valve *z*. In this manner, atmospheric air is admitted to the flaring upper 75 end of pipe *g*, and its amount is regulated by the valve *z*.

At the beginning of the operation, the drum *a* is charged with wet hides and cleaning agent, such as sand, sawdust or the like, and the heating system is started. The drum *a* and the fan *k* are now rotated. The fan *k* draws air and particles of cleaning agent from the drum *a* through the trunnion *f* and 80 stuffing box *t'* and delivers the mixture to the separator *m* through pipe *l* while at the same time the fan draws in fresh air through the pipe *c* which is heated at *q* and flows through the drum *a* from trunnion *e* to trunnion *f*.

The air which is delivered to the separator *m* through the pipe *l*, contains not only suspended particles of cleaning agent, but also vapor from the hides which are heated in the manner described while rotating with the drum *a*. At the opening of the pipe *l* into the separator *m*, the air is abruptly deflected in vertical direction and leaves the separator at *v* entraining the vapor, while the heavier particles of cleaning agent are collected in the tapering lower portion of the separator *m* and delivered to the pipe *g* and the suction pipe *c* through the comparatively narrow outlet *o*. These particles which have been dried in the heated separator, are returned to the drum *a* with the fresh air in the suction pipe *c* so that each particle, when arriving at the drum *a*, is in good condition for performing its operation on the 95 hides, and not soaked with moisture.

If desired, fresh atmospheric air is admitted to the particles at the flaring upper end of the pipe *g* by suitably adjusting the valve *z*. In this manner not only the particles which leave the separator through the outlet *o*, are accelerated by the injector action of the fresh air, but it is also possible to regulate the temperature of the heated air which flows in the suction pipe by the admixture of cold atmospheric air.

It will be understood that in this manner a continuous circulation of the cleaning agent through the apparatus is effected while the moist air is continuously discharged at *v* and replaced by the fresh air which enters at the inlet end of the suction pipe *c* and is heated and dried by the heater *q*. Moisture which has been absorbed by or adheres to, the particles of the cleaning agent, is ex- 100 105 110 115 120 125 130

- pelled by heating and/or drying the particles in the separator, as described.
- While in the apparatus described in my said copending application, the cleaning agent is retained by the perforated plates referred to, it is free to move with the flowing air in the apparatus according to the present invention, and the flow of air and suspended particles is not interfered with anywhere.
- 10 This has the advantage that a much greater quantity of air per-unit of time may be moved through the apparatus by a fan $\frac{1}{2}$ of corresponding size and capacity. The hides are never without cleaning agent as the cleaning agent is permanently returned to the drum a by the means described, while on the other hand the efficiency of the cleaning agent is increased by the drying of its particles before they are returned to the drum a . In an apparatus according to the present invention, the drying period of the hides can be better adapted to the cleaning period than in the apparatus described in my said copending application, and the processes of drying and 25 cleaning are performed in much shorter time.
- I wish it to be understood that I do not desire to be limited to the exact details of construction shown and described for obvious modifications will occur to a person skilled 30 in the art.
- In the claims affixed to this specification no selection of any particular modification of the invention is intended to the exclusion of other modifications thereof and the right to 35 subsequently make claim to any modification not covered by these claims is expressly reserved.
- I claim:—
1. An apparatus for drying and cleaning 40 hides through the medium of a gas current and solid particles suspended therein, comprising a rotary member for the reception of the hides, means for effecting a flow of gas through said rotary member, pneumatic means for separating the solid particles from the gas escaping from said rotary member, means for discharging the mechanically purified gas from the apparatus, and means for delivering the separated solid particles to the 45 gas about to enter said rotary member.
  2. An apparatus for drying and cleaning 50 hides through the medium of a gas current and solid particles suspended therein, comprising a rotary member for the reception of the hides, means for effecting a flow of gas through said rotary member, pneumatic means for separating the solid particles from the gas escaping from said rotary member, means for discharging the mechanically purified gas from the apparatus, and means for delivering the separated solid particles to the 55 gas about to enter said rotary member.
  3. An apparatus for drying and cleaning 60 hides through the medium of a gas current and solid particles suspended therein, comprising a rotary member for the reception of the hides, means for effecting a flow of gas through said rotary member, pneumatic means for separating the solid particles from the gas escaping from said rotary member, means for discharging the mechanically purified gas from the apparatus, and means for delivering the separated solid particles to the 65 gas about to enter said rotary member, and means for heating said separator.
  4. An apparatus for drying and cleaning 70 hides through the medium of a gas current and solid particles suspended therein, comprising a rotary member for the reception of the hides, means for effecting a flow of gas through said rotary member, pneumatic means for separating the solid particles from the gas escaping from said rotary member, means for discharging the mechanically purified gas from the apparatus, and means for delivering the separated solid particles to the 75 gas about to enter said rotary member, and means for heating said separator.
  5. An apparatus for drying and cleaning 80 hides through the medium of a gas current and solid particles suspended therein, comprising a rotary member for the reception of the hides, means for effecting a flow of gas through said rotary member, pneumatic means for separating the solid particles from the gas escaping from said rotary member, means for discharging the mechanically purified gas from the apparatus, and means for delivering the separated solid particles to the 85 gas about to enter said rotary member, and means for heating said separator.
  6. An apparatus for drying and cleaning 90 hides through the medium of a gas current and solid particles suspended therein, comprising a rotary member for the reception of the hides, means for effecting a flow of gas through said rotary member, pneumatic means for separating the solid particles from the gas escaping from said rotary member, means for discharging the mechanically purified gas from the apparatus, and means for delivering the separated solid particles to the 95 gas about to enter said rotary member, and means for heating said separator.
  7. An apparatus for drying and cleaning 100 hides through the medium of a gas current and solid particles suspended therein, comprising a rotary member for the reception of the hides, means for effecting a flow of gas through said rotary member, pneumatic means for separating the solid particles from the gas escaping from said rotary member, means for discharging the mechanically purified gas from the apparatus, and means for delivering the separated solid particles to the 105 gas about to enter said rotary member, and means for admixing atmospheric air to the gas about to enter said rotary member.
  8. An apparatus for drying and cleaning 110 hides through the medium of a gas current and solid particles suspended therein, comprising a rotary member for the reception of the hides, means for effecting a flow of gas through said rotary member, pneumatic means for separating the solid particles from the gas escaping from said rotary member, means for discharging the mechanically purified gas from the apparatus, and means for delivering the separated solid particles to the 115 gas about to enter said rotary member, and means for admixing atmospheric air to the gas about to enter said rotary member together with the particles from said separator.
  9. An apparatus for drying and cleaning 120 hides through the medium of a gas current and solid particles suspended therein, comprising a rotary member for the reception of the hides, means for effecting a flow of gas through said rotary member, pneumatic means for separating the solid particles from the gas escaping from said rotary member, 125 and means for admixing atmospheric air to the gas about to enter said rotary member together with the particles from said separator.
  10. An apparatus for drying and cleaning 130 hides through the medium of a gas current and solid particles suspended therein, comprising a rotary member for the reception of the hides, means for effecting a flow of gas through said rotary member, pneumatic means for separating the solid particles from the gas escaping from said rotary member,

means for discharging the mechanically purified gas from the apparatus, means for delivering the separated solid particles to the gas about to enter said rotary member, and adjustable means for admixing atmospheric air to the gas about to enter said rotary member.

8. An apparatus for drying and cleaning hides through the medium of a gas current and solid particles suspended therein, comprising a rotary member for the reception of the hides, a fan connected to one end of said rotary member at its suction side, a suction pipe connected to the opposite end of said rotary member, a separator, a discharge pipe at the upper end of said separator, a delivery pipe connecting the delivery side of said fan to said separator, and an outlet at the lower end of said separator for delivering the separated particles to said suction pipe.

9. An apparatus for drying and cleaning hides through the medium of a gas current and solid particles suspended therein, comprising a rotary member for the reception of the hides, a fan connected to one end of said rotary member at its suction side, a suction pipe connected to the opposite end of said rotary member, a separator, a discharge pipe at the upper end of said separator, a heating jacket on said separator, a delivery pipe connecting the delivery side of said fan to said separator, and an outlet at the lower end of said separator for delivering the separated particles to said suction pipe.

25 10. An apparatus for drying and cleaning

hides through the medium of a gas current and solid particles suspended therein, comprising a rotary member for the reception of the hides, a fan connected to one end of said rotary member at its suction side, a suction pipe connected to the opposite end of said rotary member, a separator, a discharge pipe at the upper end of said separator, a heater surrounding said suction pipe and so arranged as to heat said rotary member by 70 radiation, a heating jacket on said separator connected to the heater on the suction pipe, a delivery pipe connecting the delivery side of said fan to said separator, and an outlet at the lower end of said separator for delivering the separated particles to said suction pipe.

11. An apparatus for drying and cleaning hides through the medium of a gas current and solid particles suspended therein, comprising a rotary member for the reception of the hides, a fan connected to one end of said rotary member at its suction side, a suction pipe connected to the opposite end of said rotary member, a separator, a discharge pipe at the upper end of said separator, a delivery pipe connecting the delivery side of said fan to said separator, an outlet at the lower end of said separator, a pipe which is connected to said suction pipe at one end and with its other end surrounds said outlet with a clearance, and adjustable means for admitting atmospheric air to the other end of said pipe.
